Primary Examiner — Kelley A Donnelly(74) *Attorney, Agent, or Firm* — Lora J. Graentzdoerffer(57) **CLAIM**

The ornamental design for color center display, as shown and described.

DESCRIPTION

FIG. 1 is a perspective view; and,

FIG. 2 is an elevation view.

The broken-line disclosure in the views represents portions of the color center display in which the claimed design is embodied, but which forms no part of the claimed design.

1 Claim, 2 Drawing Sheets(56)
